URINAL CONSTRUCTION

Laura A. Chambers, San Francisco, Calif.

Application September 10, 1951, Serial No. 245,811

2 Claims. (Cl. 128—295)

1

This invention relates to a new and improved urinal construction.

One embodiment of the invention shown in the drawings is particularly adaptable for wear by ambulatory patients, whereas another embodiment shown, is especially adaptable for use by bed patients.

Each of the embodiments illustrated in the drawings and which will be hereinafter described in greater detail comprises, generally, a sack unit formed of a relatively pliant liquid-proof material defining a urine reservoir pouch and having a constricted or gathered neck opening in which is disposed a novel funnel and check valve assembly. Each embodiment further incorporates an enlarged mouth opening in communication with the funnel and check valve assembly and which said mouth opening is adapted for placement adjacent or over the crotch or genital regions of a user. A reinforcing ring formed of a readily deformable material, such as rubber coated wire, for example, is provided adjacent the mouth opening of the urinal to prevent collapse of material into the mouth opening and thereby maintain substantially free and unobstructed drain passage from the mouth via the funnel and check valve assembly into the interior of the urine reservoir pouch. The reinforcing ring, being made of readily deformable material, can be manually deformed to any desired shape to permit individual and comfortable fitting of the device over the crotch area of a user.

A principal object of the present invention, therefore, is to provide a urinal construction of the character above briefly mentioned which, in one embodiment or form is particularly suited for wear by ambulatory patients, and which in another embodiment or form is especially adapted for use by bed patients.

Another object is to provide a urinal of the character mentioned which may be substantially entirely disassembled to permit thorough cleansing of all individual component elements comprising the device. In this connection the present construction has an advantage over most conventional types of urinals in that the latter usually incorporate inaccessible interior elements which can not be individually removed and cleansed. As a result, such prior art devices, after a time, usually emanate an unpleasant odor making them unsuitable for further comfortable or sanitary wear.

Another object is to provide a urinal having a deformable reinforcing ring which can be in-

2

dividually adjustably deformed in shape to fit over and engage the pubic regions of a wearer, male or female, and which said ring functions to maintain the urine drain passage open and obstructed by preventing collapse or crumpling of the pliant material into the mouth or neck opening of the device.

Another object is to provide a urinal of the character above briefly mentioned, which in the case of the embodiment particularly adaptable for wear by ambulatory patients, includes a supporting garment having elements arranged to co-act with the reinforcing ring to maintain the latter snugly engaged over the genital organs of the wearer.

Other numerous objects and advantages of the present invention will become apparent upon reading the following specification and referring to the accompanying drawings in which similar characters of reference represent corresponding parts in each of the several views.

In the drawings:

Fig. 1 is an enlarged side elevation view in section of one embodiment of the invention particularly adaptable for wear by ambulatory patients.

Fig. 2 is an end elevational view of the device shown in Fig. 1.

Fig. 3 is a side elevational view of a pouch portion of the urinal shown in Fig. 1.

Fig. 4 is a perspective view of a second embodiment of the urinal particularly adaptable for use by bed patients and showing some of the parts broken away.

Fig. 5 is a side elevational view in the section of the device shown in Fig. 4.

Fig. 6 is a sectional view taken on line 6—6 of Fig. 5.

Fig. 7 is a perspective view of the wire reinforcing frame assembly.

Fig. 8 is a plan view showing the pattern cut-out from which the pouch and front and back pocket sections may be formed.

Fig. 9 is a perspective view showing the manner in which the pattern cut-out of Fig. 8 may be folded to form the pouch and front and back pocket sections of the device.

Fig. 10 is a side elevational view showing the device in wear by a bed patient.

The embodiment of the invention which is illustrated particularly in Figs. 1, 2 and 3, and to which reference is now particularly made, is especially adaptable for wear by ambulatory patients. The device illustrated comprises, generally, a sack unit A, a funnel and check-valve

assembly B, a reinforcing ring assembly C, and a supporting garment, indicated generally at D.

The sack unit of the device, hereinabove designated generally at A, is preferably formed from sections of suitable pliant, liquid-proof sheet material, such as sheet plastic, having their contiguous marginal edges stitched, heat-sealed or otherwise joined, as indicated at 11, to form a liquidtight receptacle and defining a urine reservoir pouch 10. Preferably the sack is formed with its upper side portions tapered slightly inwardly as indicated at 12, for reasons which will more fully appear hereinafter. Sack A is also preferably provided or formed with an outwardly extending drain port 13 which may be folded over itself and secured with a rubber band or the like, as indicated at 14.

The funnel and check valve assembly comprises, more specifically, a funnel element 16, preferably formed of relatively heavy rubber, which supports a depending check valve 17. Check valve 17 is shown as comprising an upper supporting ring 18 having an outwardly extending annular flange 19 adapted for removable insertion within the lower end of funnel 16. Ring 18, in turn, supports depending, hollow, finger-like element or nipple 21, circular in cross-section, and having drain aperture 22 formed in its lower end. Element 21 is preferably formed of extremely lightweight and very pliant material, such as thin sheet rubber, which will readily crumple or collapse upon any exterior pressure or force being applied thereto. More specifically, nipple 21 is preferably formed of a material which will readily collapse or bend upon any substantial quantity of urine striking against it from the urine reservoir pouch 10 and thus prevent any possibility of back-flow of urine upwardly through the funnel and check-valve assembly from the urine reservoir pouch 10. On the other hand, the material is sufficiently resilient to maintain its open tubular shape during ordinary wear thereby defining a comparatively large open drain passage, and for this reason will not clog up due to the presence of possible foreign solid substances such as lint from the patient's clothing, or such as small quantities of fecal matter which may find access into the interior of the urinal.

The reinforcing ring assembly, heretofore designated generally at C, comprises an annular wire band 23, insulated throughout its length with a relatively thick casing of rubber or suitable plastic 24. Reinforcing ring C is readily deformable and can be manually deformed into practically any desired shape to comfortably and snugly fit over the genital regions of a user, male or female.

The supporting garment, heretofore designated generally at D, comprises more specifically, an elastic waist band 26 to which is secured an elongated supporting strap, defining front and back sections, 27 and 28 respectively, and which said strap is formed with an enlarged slit or opening 29 adapted to fit over and support the urinal in a manner to be described.

In the assembly of the device hereinabove described reinforcing ring C is positioned over the upper tapered portions 12 of the sack which are then folded over said ring to maintain the latter within its folds. The funnel and check valve assembly B can then be inserted through the open mouth of the sack and securely maintained adjacent the upper portion of the sack by means of an elastic band 31. In this connection

it is noted that band 31 will serve to gather the sack material tightly around the exterior of the funnel and check valve assembly and establish in effect a constricted neck portion. Supporting ring C, disposed within folds of material 12, will function to maintain the mouth of the sack open and in unobstructed drain communication with the funnel and drain valve assembly.

The urinal may be supported to garment D by slipping slit opening 29 over the sack material into tight circumferential engagement around band 31, as shown in Fig. 2.

In actual wear, the device is supported over the urinary organs of a user with front strap 27 extending downwardly around the users' lower abdominal portions and with back strap 28 extending downwardly between his buttocks. Because the supporting ring C is made of a readily deformable material the user may adjust the mouth opening of the sack to comfortably fit over and snugly engage the patient's crotch area. Once the device has been properly adjusted to the user for wear straps 27 and 28, which engage opposite sides of ring C, as indicated at 27a and 27b, will function to maintain the mouth opening of the device in firm and snug engagement against the crotch of the user.

The embodiment of the invention illustrated particularly in Figs. 4 through 8, inclusive, and to which particular reference is now made is especially adaptable for use by bed patients.

This latter embodiment comprises, generally, a liquid-proof sack unit defining a urine reservoir pouch, indicated generally at E, and front and back pocket sections, indicated generally at F and G, respectively. The embodiment further incorporates a funnel and check valve assembly, indicated generally at H, and a reinforcing frame assembly, indicated generally at I. The pouch and front and back pocket sections may be fashioned from a single rectangular pattern cut-out, such as shown in Figs. 8 and 9, wherein it is seen how adjacent sections of the material may be folded over one another and stitched along their contiguous marginal edges to establish the aforementioned pouch and front and back pocket sections. More particularly, and as indicated in Fig. 9 adjacent sections 51 and 52 of the material may be folded along line 53 and stitched or heat-sealed, along their contiguous edges to form pouch portion E. Similarly adjacent end sections 54-55 and 57-58 may be folded along line 56 and 59 to establish pocket sections F and G, respectively. Flap members 61 and 62 may be stitched or otherwise secured to opposite sides of section G as separate cutout pattern elements.

The funnel and check valve assembly indicated generally at H is shown as being substantially identical in construction and operation to the funnel and check valve assembly B hereinabove described in detail. The component elements comprising assembly H are designated similarly to corresponding elements comprising assembly B but are suffixed by the letter "a" to distinguish them in the drawings.

The reinforcing frame assembly heretofore designated generally at I is shown as comprising a substantially rectangular frame, preferably formed of readily deformable rubber or plastic insulated wire 64, and fashioned with a centrally disposed annular reinforcing ring 65 of the same material. The entire reinforcing frame assembly may be fashioned from a single piece of insulated wire, such as shown in Fig. 7, or obvi-

ously the assembly may be fashioned from a plurality of shorter lengths of wire which may be twisted or soldered together as desired to form the completed unit.

In assembly end section 66 of wire frame 64 is inserted within the pocket opening F, established by sections 54 and 55 of the sack material. The opposite end section 67 of rectangular frame 66 is similarly disposed within pocket G. Positioning of the frame assembly in pockets F and G in the above manner will function to position annular ring 65 closely adjacent the mouth opening 68 of pouch E and thereby prevent collapse of the sack material inwardly into the mouth and funnel openings and thereby maintain substantially unobstructed open drain communication from the mouth via the funnel and check valve assembly H into the urine reservoir pouch E.

In operation the device may be positioned in assembled relationship on a bed with pocket section G extending beneath the buttocks and lower back portion of the patient, and with the patient's legs projecting either side of front pocket section F and pouch E. Positioning of the device in the above manner with respect to the patient will move the mouth opening 68 of the sack and its associated reinforcing ring 65 into close proximity and over the genital organs of the patient. In order to prevent the device from becoming displaced from its proper location with respect to the patient and further to prevent as much as possible the leakage of urine outwardly onto the surrounding bed area, complementary snaps 71 or equivalent fastening elements are provided adjacent the outer marginal side edges of pocket sections F and G to permit said pocket sections to be brought together and fastened around the lower trunk regions of the user, as shown in Fig. 10, leaving only leg openings such as indicated at 70. Prior to fastening the two sections together it is preferable to bring side flaps 61 and 62 upwardly around the sides of the patient and over his abdominal region in order to prevent leakage of urine outwardly between the pocket sections along their line of juncture.

In order to prevent skin rash which may develop upon prolonged direct contact between a patient's skin and the waterproof sack material I prefer to provide suitable diaper cloths made of cotton or other suitable absorbent material which may be easily replaced as the patient's needs may require.

More specifically, each pocket section F and G may be provided with a ribbon-tie, such as indicated at 72 and 73, respectively. The opposite

ends of the ties may be projected through suitable openings 74 and 75 formed in the sack material and removably tied to associated portions of the wire frame assembly I. Diaper cloths 76 and 77 may be suspended over the ribbon-ties, as shown in Fig. 5, and thereby prevent any substantial direct contact between the patient and the sack material.

Although the present invention has been described by way of illustration and example for purposes of clarity of understanding it is understood that certain changes and modifications may be made within the spirit of the invention and scope of the appended claims.

I claim:

1. A urinal comprising in assembled condition; a sack unit formed of a relatively pliable liquid-proof material having an open top and closed at its sides and bottom, a funnel made of relatively heavy and stiff material disposed within said sack unit below the top opening thereof, the material of the sack unit being gathered about said funnel defining a constricted neck portion, the portion of the sack unit disposed below said constricted sack portion defining a urine reservoir, a substantially annular reinforcing element made of a manually deformable nonresilient material and having a substantially larger diameter than the diameter of said constricted neck portion reinforcing the sack opening and defining an outwardly flared mouth opening for the sack unit between said reinforcing element and said mouth opening, a supporting garment comprising a waistband and front and back depending supporting straps removably affixed to and supporting said sack unit adjacent said constricted neck portion.

2. A urinal according to claim 1 and wherein said annular reinforcing element is removably engaged within a loose outward fold of the upper sack unit material.

LAURA A. CHAMBERS.
